UNITED STATES PATENT OFFICE.

WILLIAM DALTON, OF SCHENECTADY, NEW YORK.

AUTOMATIC LOW-WATER-LEVEL MARKER.

1,183,438.

Specification of Letters Patent. Patented May 16, 1916.

Application filed May 15, 1914. Serial No. 838,681.

To all whom it may concern:

Be it known that I, WILLIAM DALTON, of Schenectady, in the county of Schenectady and State of New York, have invented a certain new and useful Improvement in Automatic Low-Water-Level Markers, of which improvement the following is a specification.

My invention relates to low water level markers for steam boilers, particularly those operating on locomotive engines, and is designed to automatically present an exterior indication or mark, in all variations of position of the boiler relatively to a normal horizontal one, which will correspond to a predetermined safe level above the highest level of the crown sheet of the boiler.

The object of my invention is to provide means whereby the permissible safe low water level may be automatically and clearly indicated, regardless of variations of position of the boiler in operation, relatively to its normal horizontal position, such, for example, as are effected by the passage of a locomotive from a level to a grade, or from a horizontal portion of the track to one which is laterally inclined by the elevation of the outer rails in a curve, or vice versa, thereby guarding against destructive explosions and loss of life, due to the lack of a sufficient depth of water above the crown of the firebox.

Another object of the invention is to provide simple and effective means whereby the actual water level in a steam boiler may be at all times compared with the permissible safe low water level irrespective of the size and working inclinations of the boiler, in order that the operator may feel certain as to the actual safe amount of water over the crown sheet, the tendency to carry an excess of water being thereby avoided, and the boiler being relieved from the burden of heating an excessive amount of feed water when working at its maximum capacity in ascending a grade and preparatory to a sudden change in its inclination when reaching the summit, thus enabling a greater amount of dry steam to be furnished at a higher evaporative efficiency, with a corresponding material increase of economy and power.

A further object is to provide means whereby the accuracy and proper operation of the glass gage tube and gage cocks ordinarily applied on locomotive boilers may be checked when the locomotive is under rolling or lateral swaying movement.

The improvement claimed is hereinafter fully set forth.

In the accompanying drawings: Figure 1 is a vertical longitudinal section, taken on the line A A of Fig. 2, through the rear or firebox end of a locomotive boiler, illustrating an application of my invention; Fig. 2, a rear view, in elevation; and Fig. 3, a plan or top view.

My invention is herein exemplified as applied in a large locomotive boiler, of the semi-wide firebox type, comprising, as in ordinary practice, a firebox, 1, which is closed at top by a crown sheet, 2, and is connected to a shell, 4, through which a plurality of fire tubes, 3, extends from the tube sheet, 5, to a smoke box (not shown) at the front end of the boiler. As in all properly designed boilers of this type, the height of the water and steam space between the crown sheet and the shell, is necessarily comparatively limited to avoid excessive external dimensions of the boiler and afford the requisite clearance from bridges, tunnels, and vehicles on parallel tracks. In locomotives designed for heavy grade or mountain service, it is of special and urgent importance to insure the maintenance of a sufficient depth of water over the crown sheet, particularly when operating at full power on heavy grades, to avoid risk of destructive explosions and resultant loss of life and damage to property. In practice, it is usual to allow approximately from three to four inches over the crown sheet, 2, (which is generally inclined downwardly toward the back head of the boiler,) adjacent to the firebox tube sheet, 5, and it is clearly not within the bounds of prudence to assume that a safe allowance of water depth may be insured in a large locomotive boiler, having a length of as much as forty one feet of water surface, by the mere observation of a water glass gage located on the back head, 6, of the boiler, which may be sixteen feet or more in rear of the "critical" point of level, which is at the highest level of the crown sheet where it adjoins the tube sheet, 5.

By the descriptive term "critical point", as herein applied, there is meant a point located a minimum safe distance above the highest point of the crown sheet or other surface exposed to direct furnace heat, below which point the water level in the boiler must never, consistently with safety, be permitted to fall. This limitation of warranted

assumption is particularly important when the locomotive is operating on mountain roads in which there are continual changes in the grades and curvatures, and wherein the rail elevations on curves cause the locomotive to frequently sway from side to side.

To enable the operator to maintain a safe water depth over the crown sheet, my invention is designed to indicate, by observation at one or more points exterior to the boiler, a precise measure of the level of water at the critical point on the crown sheet, regardless of longitudinal or traverse inclination of the boiler.

In the practice of my invention, I provide two small reservoirs, 7^a, which are supported outside the boiler, on opposite sides thereof, above the level of the crown sheet, 2^a, and preferably adjacent to the plane of the firebox tube sheet, 5. The reservoirs, which are supplied with a suitable leveling liquid, preferably mercury, are made of sufficient length to accommodate the total rise and fall of the corresponding liquid surfaces due to the difference of level of the opposite track rails, and the sum of the areas of their bores is substantially greater than the area of the bore of a tubular indicator or automatic marker glass, 14, connected to and supported on the back boiler head, 6. For purposes of simplicity and ready comparison, the automatic marker glass is disposed parallel with and adjacent to the ordinary water glass gage, 21, and may be secured to the support or mounting thereof.

Each of the reservoirs, 7^a, is connected by one of a pair of horizontally disposed conduits, 42, extending on the outside of the firebox, with the automatic marker glass, 14, the conduits communicating one with the other, and with the glass, through a T fitting, 43, a leveling liquid level being thereby formed and maintained in the two reservoirs and the glass. The vertical distance between this leveling liquid level and the critical point, 2^a, which is located preferably at the highest level of the crown sheet adjoining the firebox tube sheet, 5, is a measure of the safe allowable minimum depth of water over the crown sheet, and varies in amount in boilers of different designs and different service requirements. It is often found desirable to attach an automatic marker glass, 41, to each reservoir, and to locate a water gage glass, 40, adjacent to each reservoir, thereby providing at least three observation points, which would be more particularly useful in locomotives in which the cab is located forward of the firebox. By properly proportioning the reservoirs, an automatic marker glass and water gage glass may be located at any other desirable observation point, and the glasses, 40 and 41, adjacent to the reservoirs may be omitted.

The combined area of the bores of the reservoirs, 7^a, is greater, in a predetermined ratio, than that of the bore of the marker glass, 14. It will be obvious that if this ratio was indefinitely great, no change of elevation of the level of the liquid surfaces would take place relatively to the level of the critical point on the crown sheet, when the locomotive, in running forward, passes over the summit of a grade and moves on a down grade. It is important, in practice, to insure greater safety by increasing the allowable depth of water over the crown sheet when the locomotive boiler points down grade, in which operating position the water level naturally lowers over the crown sheet and rises at and toward the front or smoke box tube sheet. In order to provide for this desirable increase, the proportioning of the relative diameters of the reservoirs and marker glass is based upon the design of the boiler and the character of the service in which it is to be operated. Thus, for illustration, if the combined areas of the bores of the reservoirs be, say, thirty times that of the bore of the marker glass, and the distance between the reservoirs and glass be, say, fifteen feet, a "drop" of six inches in the level of the liquid surface in the glass would correspond with an elevation of the liquid surfaces of one-fifth of an inch, relatively to the critical point. This amount of permissible increase of water depth over the crown sheet, may, of course, be changed, by variation of the ratio of the bores in accordance with the structure and character of service of the boiler, which capacity of providing for change in the allowable water depth is an important and valuable feature of my invention.

In the erection of a locomotive, it is the usual practice, after the boiler is mounted in a level position on the locomotive frame, to permanently secure to the back head, 6, a stationary marker, 20, which corresponds with the allowable safe minimum low water level over the critical point in the crown sheet. After the locomotive is under steam, at normal working pressure and temperature, the elevation of the stationary marker, after which the automatic marker can always be checked when the boiler is in a known level position.

Under normal working conditions, the water surface in the ordinary gage glass, 21, corresponds in elevation with the actual water surface within the boiler, and the difference in the elevation of the liquid surfaces in the indicator, 14, and glass, 21, gives an accurate measure of the excess of water level in the boiler above the permissible minimum safe low water level. The liquid surfaces

in the indicator and glass will simultaneously rise and fall in a given inclination of the boiler, the relative amount of movement depending largely upon the design of the boiler, and the most desirable design giving the smallest change in the distance corresponding to the difference of level in the indicator and glass. This feature of my invention is of value in the comparison and selection of designs of boilers most suitable for railroads having many changes in grade. A graduated marker, combined with the fixed marker, and indicating percentage of grade, is useful and convenient for determining the track grade.

The upper ends of the reservoirs, 7^a, may, if desired, be connected through pipes, 48, a T fitting, 46, and a pipe, 47, with the top of the automatic marker glass, 14, and further, it is essential that said reservoirs shall be connected, below the liquid level by a transverse pipe, 49, for the purpose of causing the level of the liquid in either reservoir to be maintained at the level of the critical point. A complete closed intercommunicating circuit will thereby be formed, which includes the reservoirs, 7^a, conduits, 42, glasses, 14, 40 and 41, and pipes, 47, 48 and 49. The pipes, 47 and 48, are, in practice, omitted, with the object of simplification. The transverse pipe, 49, causes the liquid levels to quickly correspond to lateral inclination or swaying of the boiler.

My invention is of substantial practical merit and value in the particular of providing ready and effective means for detecting at all times any defect in the operation of the water level indicators ordinarily applied to locomotive boilers, as, for example, when a water gage cock or a water glass fitting becomes clogged by sediment or scale formation, a comparison of the relative positions and movement of the leveling liquid and the water level indicator reading will promptly show defective operation of the water level indicator. In such case, the movement of the water in the gage is relatively sluggish, and induces false readings, which are not in correspondence with the changing inclinations of the boiler. The latter are quickly and accurately indicated by the inclosed and protected leveling liquid.

An embodiment of my invention in which only a single reservoir is applied, constitutes the subject matter of a divisional application filed by me September 21, 1915, Ser. No. 51833.

I claim as my invention and desire to secure by Letters Patent:

1. The combination, with a steam boiler of a type which is subject to rolling or pitching movements in service of a water level

marker comprising two reservoirs, each adapted to contain a portion of a leveling liquid, said reservoirs being so proportioned relatively to an indicator and disposed on opposite sides of the boiler in position to maintain a relatively large surface of such liquid at a level corresponding with the level of a predetermined critical point within the boiler, an indicator adapted to inclose another portion of such liquid and maintain and indicate a relatively small surface thereof, at the same level, and a conduit connecting said reservoirs and indicator, below the surfaces of the contained liquid.

2. The combination, with a steam boiler of a type which is subject to rolling or pitching movements in service, of a water level marker comprising two reservoirs, each adapted to contain a portion of a leveling liquid, said reservoirs being so proportioned relatively to an indicator and located on opposite sides of the boiler in position to maintain a relatively large surface of such liquid at a level corresponding with the level of a predetermined critical point within the boiler, an indicator adapted to inclose another portion of such liquid and maintain a relatively small surface area thereof, at the same level, a conduit connecting said reservoirs and indicator, below the surfaces of the contained liquid.

3. The combination, with a steam boiler of a type which is subject to rolling or pitching movements in service, of a water level marker comprising two reservoirs, each adapted to contain a portion of a leveling liquid, said reservoirs being of materially greater capacity than that of the indicator hereinafter specified, and being so proportioned relatively to said indicator and located on opposite sides of the boiler in such position as to maintain a relatively large surface of the leveling liquid, at a level corresponding with the level of a predetermined critical point within the boiler, an indicator adapted to inclose another portion of such liquid, and maintain a relatively small surface area thereof at the same level, a reservoir conduit extending downwardly below the boiler, from each reservoir, and a supplementary conduit connected therewith and with the indicator for the purpose of establishing and maintaining leveling liquid communication between said reservoirs and indicator.

WILLIAM DALTON.
